(57) **CLAIM**

The ornamental design for a lid for a container, as shown and described.

DESCRIPTION

FIG. 1 is a perspective top, front and right side view of a lid for a container showing my new and ornamental design,

FIG. 2 is a top plan view thereof,

FIG. 3 is a bottom plan view thereof,

FIG. 4 is a front elevational view thereof,

FIG. 5 is a rear elevational view thereof,

FIG. 6 is a left side elevational view, thereof

FIG. 7 is a right side elevational view thereof,

FIG. 8 is a perspective bottom, front and right side view thereof; and,

FIGS. 9-16 are views similar to FIGS. 1-8 showing the lid on a container.

Features depicted in broken lines do not constitute parts of the claimed design.
